UNITED STATES PATENT OFFICE

2,668,405

MATTRESS WINDING AND WRAPPING MACHINE

Joseph W. Droll, Chicago, Ill., assignor, by mesne assignments, to Meridan Corporation, Providence, R. I., a corporation of Rhode Island

Application January 29, 1951, Serial No. 208,278

12 Claims. (Cl. 53—52)

1 The invention relates to mattress wrapping machines.

One object of the invention is to provide a machine for conveniently and expeditiously wrapping mattresses.

Another object of the invention is to provide a machine of this type which includes an expandable mandrel for gripping the leading end of the web of wrapping paper, and is contractible to release the paper and the wrapped mattress for its endwise withdrawal from the mandrel.

Another object is to equip a mattress wrapping machine with improved mechanism for reversing the portion of the paper wrapped around the mattress from the web from a supply roll.

Another object is to provide improved mechanism for automatically stopping the rotation of the mandrel after a predetermined number of revolutions.

Another object is to provide a mattress wrapping machine which is efficient, has a high capacity, and can be conveniently controlled in its operation.

Other objects will appear from the detailed description.

The invention consists in the novel features hereinafter set forth and more particularly defined by claims at the conclusion hereof.

In the drawings:

Fig. 1 is a perspective view of a machine embodying the invention;

Fig. 2 is a front elevation;

Fig. 3 is a longitudinal section taken on line 3—3 of Fig. 2;

Fig. 3a is a detail perspective view of the bar carried by the mandrel for indicating the extent of extra revolutions of the mandrel;

Fig. 4 is a side elevation of the portion of the machine in front of the rolls of wrapping paper;

Fig. 5 is a section taken on line 5—5 of Fig. 4;

Fig. 6 is a longitudinal section illustrating the position of a mattress on the front table section at the commencement of a winding operation;

Fig. 7 is a similar view illustrating a mattress partially wound and wrapped;

Fig. 8 is a section taken on line 8—8 of Fig. 4;

Fig. 9 is a central longitudinal section illustrating the cutter mechanism for severing a sheet wound around the mattress from the web from a supply roll;

Fig. 10 is a section taken on line 10—10 of Fig. 9;

Fig. 11 is a section taken on line 11—11 of Fig. 9;

Fig. 12 is a transverse section illustrating the

2 clutch for the gearing for driving the mandrel, parts being shown on elevation;

Fig. 13 is a section taken on line 13—13 of Fig. 12;

Fig. 14 is a perspective view of the dog for holding engaged and releasing the clutch for driving the mandrel;

Fig. 15 is a perspective of the stud engaged by said dog;

Fig. 16 is a longitudinal section of the collapsible mandrel in its expanded position;

Fig. 17 is a transverse section taken on line 17—17 of Fig. 16;

Fig. 18 is a section taken on line 18—18 of

Fig. 16, the mandrel being collapsed;

Fig. 19 is a partial section taken on line 19—19 of Fig. 18, the mandrel being shown collapsed;

Fig. 20 is a partial section taken on line 20—20 of Fig. 17, the mandrel being shown expanded in full lines;

Fig. 21 is a transverse section taken on line 21—21 of Fig. 4; and

Fig. 22 is a diagram of the electrical connections of the circuit for controlling the cutter mechanism.

The invention is exemplified in a machine which comprises a supporting framework which includes a pair of side frames 25, a cross frame 26, a cross frame 27 and cross bars 28 and 29, all secured together to form a rigid structure. The rear portion of the side frames 25 is provided with open ended bearings 30 for supporting the cores of a series of rolls of paper 31 for wrapping the mattresses. These rolls of paper may be of different weight or color for selective use in wrapping the mattresses. A rear table section 33 has a tube 34 fixed to its front edge and said tube is pivotally and removably supported in open ended bearings on the side frames 25. Table section 33 is supported in its horizontal position by legs 36 which are pivoted to said section at 37 and toggle braces 38 between said legs and the central portion of said table section. Legs 37 rest on lugs 39 on side frames 25. Table section 33 and its supporting legs may be swung upwardly in the bearings for tube 34, or the legs 36 may be collapsed. The table section 33 may be bodily removed from the supporting frame for access to a web of paper from one of the rolls 31 or to the mechanism beneath table section 33. A front table section 42 has fixed to its rear end a tube 43 which is pivotally confined in open ended bearings in side frames 25 and has its front end supported by a pair of levers 44 which are connected by a shaft 45 which is pivotally supported in bearings 45' on cross frame 26.

The front ends of levers 44 are connected by links 46 to the under side of table section 42 and their rear ends are provided with weights 47 for urging table sections 42 against a mattress thereon and pressing it against the mandrel herein-after described. Table sections 33 and 42 are adapted to receive a mattress and to slidably support it while it is being wound and wrapped, and the front table section is adapted to receive under the mattress a strip of paper from one of the rolls 31. The web of paper from the selected roll 31 is fed forwardly by a rubber covered roll 50 which is journalled in side frames 25 and a coacting weighted roller 51 which is slidably and rotatably supported in open-ended bearings 52. From rollers 50 and 51 the web of paper passes through a gap between the front end of rear table section 33 and the rear end of front table section 42, and onto the top face of said front table section. Roller 51 may be held separated from roll 50 for convenience in threading the web between them, by a pedal 55 on a shaft 56 which is fulcrumed on cross frame 27, arms 59 pivoted on side frames 25 and adapted to lift rollers 51 and links 58 connected to pedal 55 and to lifter arms 59. A spring-pressed latch 59 pivoted on one of the side frames is adapted to hold pedal 55 in position to hold roller 51 raised while the web is threaded between rollers 50 and 51.

A collapsible mandrel generally designated 69 is provided for spirally winding the mattress and wrapping a strip of the web of paper around the mattress. The mandrel comprises a sleeve 61 which is journalled in a bearing 62 on one of the side frames 25, a pair of inner peripheral sections 64 having outwardly convergent sides 65 and a pair of outer peripheral sections 66 having outwardly convergent sides 67 overlapping the sides 65 of the inner sections 64. One end of sleeve 61 is supported in bearing 62 and the opposite end of the mandrel is free to permit end-wise removal of the wrapped mattress from the mandrel. Longitudinal reinforcing bars 68 are fixedly welded to the inner faces of sections 64 and longitudinal reinforcing bars 69 are welded to the inner faces of said sections. The sections 64 are shiftable radially for clamping the free end of a wrapping strip between the overlapping end portions of the sides 65 and 67 of the mandrel sections by a stem 74 which is slidable in sleeve 61 and is connected by a pair of parallel linkages to one pair of bars 68. Each of single linkages comprises a pair of links 75 and 76 having their inner ends connected by a pivot pin 77 to stem 74 and their outer ends pivoted at 78 to one of the bars 68. Each inner section 64 is connected to the stem 74 by a pair of parallel linkages, each of which includes a pair of links 79, having their inner ends pivoted in stem 74 at 77 and their outer ends pivoted at 78 to one of the reinforcing bars. The links of the linkages for the inner and outer mandrel sections are of differential length so that sections when expanded will close the gaps between them and grip an end of the wrapping paper. The mandrel is contractible to reduce its diameter and permit end-wise removal of wrapped mattress from the mandrel and to spread apart the convergent side of the inner and outer sections to release the end of the wrapping paper. All sections of the mandrel are confined against substantial longitudinal movement by links 80 which are pivoted at 81 to a collar 82 which is fixed to sleeve 61 and at 83 to a reinforcing bar 68. When the mandrel is expanded, the overlapping convergent sides of

the inner and outer sections of the mandrel are adapted to grip one end of the paper strip between them, and when the inner sections are collapsed, the end of the strip can be inserted between the contiguous sides of an inner and outer section. When the stem 74 is in the position illustrated in Figs. 18 and 19, the toggle links will be collapsed and hold the inner sections 65 in position to permit insertion of the end of a strip of paper between the inner and outer sections of the mandrel. When the stem 74 is in the expanded position illustrated in Fig. 17, the end of the paper strip will be gripped between the overlapping sides of an inner and an outer section, and said sections will be locked by the toggle links to retain said end in the mandrel, so that upon rotation of the mandrel the paper and mattress will be spirally wound around the mandrel as a core. When the mandrel is collapsed after a mattress has been wrapped, the diameter of the mandrel will be reduced to permit the free endwise withdrawal of the mattress from the mandrel and simultaneously release the inner end of the wrapper.

The stem 74 of the mandrel is slidable in sleeve 61 for operating the mandrel sections into expanded and contracted positions by a device which comprises a two-arm rocker lever 120 (Fig. 2) which is centrally fulcrumed on cross frame 26, a pair of pedals 121 and 122 operatively connected by links to the ends of the arms on the rocker lever respectively, a link 123 pivoted to one arm of lever 120 and to the lower end of a lever 124 which is fulcrumed at 125 on one of the side frames 25 and a collar 127 which is connected to the outer end of stem 74. The collar 127 is connected to stem 74 by screw studs 129 which extend into a groove in said stem for slidably shifting and permitting rotation of said stem. When pedal 121 is depressed it will rock lever 120 to operate link 123, lever 124 and collar 127 and slide stem 74 outwardly in sleeve 61 into the position shown in Figs. 18 and 19. The inner mandrel sections 65 will then be separated inwardly from the outer sections 67 so that the end of the strip of wrapping paper can be inserted between convergent sides of an inner and an outer section as shown in Fig. 18. A stop pin 130 limits the inward movement of section 65. When pedal 122 is depressed, stem 74 will be shifted inwardly in sleeve 61 to expand the toggle linkages 75 and 76 and force the inner sections 65 into position to clamp the end of the wrapping strip against one of the outer sections 67, and grip the strip, and also to expand the mandrel as illustrated in Fig. 17 so that when the mandrel is rotated, the end of the strip of paper and the mattress will be spirally wound around the mandrel. The links 80 between collar 82 and the reinforcing bars on the mandrel sections hold said sections against substantial longitudinal movement relatively to sleeve 61.

The mandrel is selectively driven by gearing operated by an electric motor 90 which is mounted on a bracket 91 on one of the side frames 25, for winding a mattress thereon and simultaneously wrapping a strip of the paper around the mattress. This gearing comprises a worm wheel 93 on the shaft of motor 90, a worm gear 94 meshing with wheel 93 on a shaft 95 which is journalled in a bracket 96 and a bearing 97 on one of the side frames 25, a two-way clutch which includes a slidable member 98 on shaft 95 and a member 99, a pinion 100 fixed to and rotatable by coupling member 99, and a gear 101 fixed to sleeve 61 of the mandrel. Coupling

member 98 is held normally disengaged from member 99 by a spring 102 and is manually shiftable into driving relation with member 99 by a lever 104 which is fulcrumed at 105 on bracket 91, a link 106 which is pivoted to the lower end of lever 104, a double-arm rocker lever 107 which is fulcrumed at 108 on a bracket fixed to cross frame 26, and a pedal 109 which is connected by a link 110 to an arm on rocker lever 107 for shifting link 106 and lever 104 to engage coupling members 98 and 99 to drive pinion 100, gear 101 and sleeve 61 of the mandrel. This coupling is automatically controlled to stop the mandrel after a predetermined number of revolutions to wind the mattress around the mandrel and wrap the strip of paper around the mattress. For this purpose, a latch 110 is pivoted at 111 to the upper end of lever 104 and is urged upwardly by a spring 112. A tooth 113 on latch 110 is adapted to slip into a notch 114 in a stud 115 which is fixed to one of the side frames 25. When the clutch members 98 and 99 are disengaged, tooth 113 engages the underside of stud 115 and when said members are coupled said tooth snaps into notch 114 and holds lever 104 to hold said members in coupled relation. The latch 110 is automatically released at the end of a predetermined number of revolutions of the mandrel by a pinion 117 which rotates with gear 101, a gear 118 meshing with gear 101 and a striker bar 119 which is adjustably fixed to one side of gear 118 and is adapted to engage latch 110 to disengage tooth 113 from notch 114 against the force of spring 112 at the end of each revolution of gear 118.

The machine comprises mechanism for severing the trailing end of the strip of paper behind the mandrel and at the gap between the front section 42 and the rear section 33 of the mattress-supporting table. This mechanism includes a rotary cutter disk 135 which is adapted to travel transversely across the web of paper under a cross bar 137 and at the front edge of an inclined bed 136 over which the web of paper passes from the rollers 50 and 51 to the front table section 42. Disk 135 is journaled on a stud 138 which is supported in a carriage 139 which is movable transversely in the frame and is provided with rollers 140. Carriage 139 extends between a pair of spaced channel tracks 141 in which rollers 140 are adapted to travel. Tracks 141 extend through the side frames 25 and have their ends fixedly secured in brackets 142 which are fixed to the outer sides of said frames. A sprocket wheel 143 is fixed to rotate disk 135 and meshes with a sprocket chain 144 which is held in engagement with sprocket wheel 143 by a track 145 which is fixed to carriage 139. Each end of chain 144 is connected to a bracket 142 on a side frame 25 by means of a block 147 on a screw stud 148 which extends through a lug 149 on bracket 142 and is provided with a nut 150 for taking up the slack in or adjusting chain 144. As carriage 139 travels along tracks 141 transversely between side frames 25, the stationary chain 144 will rotate sprocket wheel 143 and disk 135 will rotate through the web of paper and sever it at the front edge of bed 136.

Reciprocating strokes are imparted to the cutter disk 135 and carriage 139 by a reversible electric motor 154, an endless sprocket chain 155 which extends around and between a pair of sprocket wheels 156 which are journaled in bracket 142, a shaft 158 to which one of the sprocket wheels 156 is fixed, and a worm gear 158 which is fixed

to shaft 158 and is driven by a worm wheel 160 on the shaft of motor 154. The starting of motor 154 is selectively controlled by an electric drum-type switch 162 and its stopping is automatically controlled for strokes of predetermined length of the cutter disk and its carriage, by a pair of limit switches 163 and 164 which are mounted on a pair of angle rails 165 fixed to the side frames 25. The actuating arm of limit switch 161 is shifted to open the circuit for motor 154 connected thereto by a spring-pressed cam arm or shoe 167 mounted on rails 165 and adapted to be depressed by the cutter carriage 139 after the cutter has completed a transverse cut of the web of paper in one direction. The actuating arm of limit switch 164 is shifted to open the circuit for motor 154 by a spring-pressed cam arm or shoe 168 mounted on rails 165 and adapted to be depressed by the carriage 139 after the cutter 135 has completed a transverse cut of the web in the opposite direction.

Feed roll 50 is adapted to be selectively driven to selectively feed the web of paper forwardly after a strip has been wrapped around the mattress and severed from the web, by a sprocket chain 171 between a sprocket wheel 170 fixed to drive roll 50 and a sprocket wheel 172 loosely mounted on shaft 95 and adapted to be coupled by slideable clutch member 98 to shaft 95 which is adapted to be driven from motor 90. A pedal 174 is connected by a link to an arm of rocker 107 and when said pedal is depressed it will shift link 106 and lever 104 to couple clutch member 98 and sprocket wheel 172 for driving feed roll 50 from shaft 95. A hood 175 is removably secured to the supporting frame for enclosing the gearing on one side of the frame.

A roll of adhesive tape 176 is mounted in a dispensing device 177 which is mounted on the hood 175 and positioned so that a strip of the tape may be pulled from the roll and energized and then applied across the edge of the sheet wrapped around the mattress.

The operation of the machine will be as follows: The end of the web of paper from the selected roll 31 is placed between the feed rolls 50 and 51. The table section 33 may be swung upwardly for access to said rolls. Pedal 155 will be depressed to shift link 58 and arm 57 to raise roll 50 above roll 51, and said pedal may be secured by latch 59 to hold roll 51 raised while the leading end of the paper is placed between rolls 50 and 51. The latch 59 is then shifted to release pedal 155 so that roll 51 will engage the paper. Next the operator will depress pedal 174 to engage clutch member 98 and sprocket wheel 172 so that chain 171 will be driven by motor 154 and will drive sprocket wheel 170 and feed roll 50 until the web of paper is advanced to overlap the table section 42 and its leading end can be connected to the mandrel. The operator will then depress pedal 109 to shift rocker 107 into its neutral position and uncouple clutch member 98 from sprocket wheel 172 to stop the advance of the web of paper when the leading end is in the position desired. Next, a mattress will be moved forwardly onto the paper on table section 42 and over table section 33 with its leading end adjacent the collapsed mandrel. The leading end of the paper will then be inserted between one of the overlapping portions of contiguous inner and outer mandrel sections which are then spaced apart. Next, the operator will depress pedal 122 to shift link 123 and lever 124 and slide stem 74 inwardly in sleeve 61. The linkages between said

stem and the inner and outer mandrel sections will be operated to cause two coacting sections to grip the leading end of the paper and the mandrel will be expanded for engagement with the adjacent mattress. This operation of stem 74 will operate the linkages to differentially shift the inner and outer sections for closing the gap between them when they are expanded and gripping the paper and increasing the diameter of the mandrel to engage the underlying front end of the mattress sufficiently to cause the mattress to be pressed upwardly against the mandrel by the weighted table section 42 during the rotation of the mandrel. Next, the operator will depress pedal 109 to shift link 106, lever 104 and clutch member 98 into engagement with clutch member 99 on pinion 100 while the motor 154 is running. The mandrel will then be rotated from clutch member 98 by pinion 100 and gear 101 which is keyed to the sleeve 61 of the mandrel. When lever 104 is shifted to engage clutch members 98 and 99, it will move dog 110 inwardly so that tooth 113 on said dog snaps into notch 114 in stud 115 and the clutch member 98 will be held engaged with clutch member 99 against the force of spring 102 until the mandrel has been rotated a sufficient number of revolutions to complete a winding and wrapping operation. The striker 119 on the gear 118, when it completes a revolution and after each winding operation has been completed, will engage dog 110 and release it from stud 115 and permit spring 102 to disengage clutch members 98 and 99 and stop the mandrel. During this predetermined rotation of the mandrel, the mattress and paper will be spirally wound around the mandrel until the mattress has been completely wrapped. When the mandrel stops, there will be a trailing portion of paper of sufficient length overlying table section 42 between the trailing end of the mattress and the transverse line of travel of the cutter disk 135 for overlapping and enclosing the trailing end of the mattress. Next, the cutter disk is operated across the paper to sever it from the web. Next, the free trailing portion of the sheet is folded to overlap the outer end of the spirally wound mattress and adhesively secured to seal the paper around the mattress by a strip of adhesive tape drawn from the roll 176 and secured across the joint between the end and an overlapped portion of the wrapper. For a cutting operation of the web, the operator will shift switch 162 into position to close a circuit and start motor 154 in one direction while the cutter carriage 139 is positioned outwardly of one side of the web of paper. The endless chain 155 driven by motor 154 will shift the carriage 139 and the stationary chain 144 will rotate the cutter disk 135 as it travels across the web of paper. When the carriage 139 engages the cam or arm 167, said arm will be depressed and open the limit switch 163 and the circuit for the motor to stop the motor and cutter-carriage after the web has been severed. At the end of the next wrapping operation, switch 162 will be shifted to close a circuit for operating the motor 154 in the opposite direction. This circuit will be through the limit switch 164 so the motor will operate the carriage 139 to shift the cutter 135 across the web of the paper in the opposite direction until the carriage opens the limit switch 164. In this manner, the cutter is alternately operated in opposite directions and automatically stopped at the end of each cutting operation.

After the mattress has been wrapped and the

5 wrapper has been sealed around the mattress, the operator will depress pedal 122 to shift link 123 and lever 124 to move the stem 74 outwardly in sleeve 61 of the mandrel. Stem 74 will operate the linkages between it and the inner and outer mandrel sections to contract the mandrel and release the inner end of the paper. During this operation, the mandrel sections will be contracted so that the wrapped mattress can be removed endwise from the mandrel after the wrapped mattress has been removed from the mandrel. The projecting portions of the wrapper, which is of greater width than the mattress, are folded and sealed around the ends of the mattress.

In some instances, it is desirable to wrap more than predetermined convolutions around the spirally wound mattress. For this purpose, the pedal 109 will be depressed by the operator to sufficient distance to engage clutch members 98 and 99 without locking dog 110 into the notch 114 in the stud 115. Said pedals will be held depressed until the added convolutions of paper have been wrapped around the mattress and then released. A bar 172 is slidably mounted on the 20 inside of one of the mandrel sections 64 and provided with a radial pin 173. When bar 172 is pulled outwardly, the pin 173 will be visible as the mandrel rotates to indicate to the operator the additional revolutions of the mandrel and the mandrel will be stopped when desired.

25 The invention is not to be understood as limited to the details described, since these may be modified within the scope of the appended claims without departing from the spirit and scope of the invention.

30 Having thus described my invention, what I claim as new and desire to secure by Letters Patent is:

1. A mattress wrapping machine comprising: 35 a table for supporting a mattress with an underlying web of paper; a rotatable mandrel over the table and including collapsible and expandable sections having overlapping peripheral members for gripping the web between them; mechanism for rotating the mandrel to wind the mattress thereon and wrap the paper around the mattress; and means for expanding the mandrel and gripping the end of the web of paper between overlapping members of the sections and contracting the mandrel to reduce its diameter for releasing the mattress and separating the members from one another to release the paper, the mandrel being unsupported at one of its ends for endwise removal of the wrapped mattress.

2. A mattress wrapping machine comprising: 40 a table for supporting a mattress with an underlying web of paper; a rotatable mandrel over the table and including collapsible and expandable sections having overlapping peripheral members for gripping the web between them, mechanism for rotating the mandrel to wind the mattress thereon and wrap the paper around the mattress; means for urging the table against the mattress to press it against the mandrel; and means for expanding the mandrel and gripping the end of the web of paper between overlapping members of the sections and contracting the mandrel to reduce its diameter for releasing the mattress and separating the members from one another to release the paper, the mandrel being unsupported at one of its ends for endwise removal of the wrapped mattress.

3. A mattress wrapping machine comprising: 45 a table for supporting a mattress with an under-

lying web of paper; a rotatable sleeve; a mandrel carried by the sleeve over the table and including collapsible and expansible sections having overlapping peripheral members for gripping the web between them, mechanism for rotating the sleeve and mandrel to wind the mattress on the mandrel and wrap the paper around the mattress; a stem slidably mounted in the sleeve; and means operable by the stem for expanding the mandrel and gripping the end of the web of paper between overlapping members of the sections and contracting the mandrel to reduce its diameter for releasing the mattress and separating the members from one another to release the paper, the mandrel being unsupported at one of its ends for endwise removal of the wrapped mattress.

4. A mattress wrapping machine comprising: a table for supporting a mattress with an underlying web of paper; a rotatable sleeve; a rotatable mandrel carried by the sleeve over the table and including collapsible and expansible sections having overlapping peripheral members for gripping the web between them, mechanism for rotating the sleeve and mandrel to wind the mattress on the mandrel and wrap the paper around the mattress; a stem slidably in the sleeve; and toggle links operable by the sleeve for expanding the mandrel and gripping the end of the web of paper between overlapping members of the sections and contracting the mandrel to reduce its diameter for releasing the mattress and separating the members from one another to release the paper, the mandrel being unsupported at one of its ends for endwise removal of the wrapped mattress.

5. A mattress wrapping machine comprising: a table for supporting a mattress with an underlying web of paper; a rotatable sleeve; a rotatable mandrel over the table and including collapsible and expansible pairs of oppositely disposed sections having overlapping peripheral members for gripping the web between them, mechanism for rotating the sleeve and mandrel to wind the mattress thereon and wrap the paper around the mattress; and differential toggle links between the pairs of oppositely disposed members and the stem for expanding the mandrel and gripping the end of the web of paper between overlapping members of the sections and contracting the mandrel to reduce its diameter for releasing the mattress and separating the members from one another to release the paper, the mandrel being unsupported at one of its ends for removal of the wrapped mattress.

6. A mattress wrapping machine comprising: a frame; front and rear mattress-supporting table sections with a gap therebetween; a pair of rolls under the rear section for feeding a web of paper through the gap and onto the front section; the rear section being supported to swing vertically in the frame to provide access to the feed rolls; means for holding one of the rolls separated; an expansible and contractible mandrel over the front table section; mechanism including a motor and a clutch for rotating the mandrel for winding the mattress thereon and wrapping the web of paper around the mattress; a pedal on the front of the frame for shifting the clutch; means for expanding the mandrel to grip the paper and for contracting the mandrel to release the mattress including pedals at the front of the frame; pedals on the front of the machine for operating the means for collapsing and contracting the mandrel, and means for

yieldingly urging the front table section to press the mattress against the mandrel.

7. A mattress wrapping machine comprising: a frame; front and rear mattress-supporting table sections with a gap therebetween; rolls under the rear section for feeding a web of paper through the gap and onto the front section; motor-driven gearing for driving said rolls and including a clutch; an expansible and contractible mandrel over the front table section; mechanism including a motor and a clutch for rotating the mandrel for winding the mattress thereon and wrapping the web of paper around the mattress; pedals on the front of the frame for controlling the clutches for driving the feed rolls and the mandrel respectively; means for expanding the mandrel to grip the paper and for contracting the mandrel to release the mattress including pedals at the front of the frame; and means for yieldingly urging the front table section to press the mattress against the mandrel.

8. A mattress wrapping machine comprising: a frame, front and rear mattress-supporting table sections with a gap therebetween; rolls under the rear section for feeding a web of paper through the gap and onto the front section; mechanism including a clutch for driving the feed rolls; an expansible and contractible mandrel over the front table section; mechanism for rotating the mandrel for winding the mattress thereon and wrapping the web of paper around the mattress; pedals at the front of the frame for controlling the clutches, respectively; and means for expanding the mandrel to grip the paper and for contracting the mandrel to release the mattress including pedals at the front of the frame.

9. In a mattress wrapping machine, a frame, a stationary generally horizontal rear table section on said frame for slidably supporting the trailing portion of the mattress, a front table section movably mounted on said frame for supporting the leading portion of the mattress, a mandrel journaled on said frame to extend across said front table section, means for moving said table section upwardly to move the front portion of the mattress toward said mandrel, said front and rear table sections having a gap therebetween through which extends a web of wrapping paper, means for guiding the paper from under the rear table section through the gap between said table sections and onto said front table section, said mandrel being expansible and contractible and being provided with means for gripping the leading edge of the paper, power means for rotating said mandrel to wind the paper and the mattress around said mandrel, and means for expanding and contracting said mandrel and to grip and release the paper, and to release the rolled mattress therefrom.

10. In a mattress wrapping machine, a frame, a stationary rear table mounted on said frame for slidably supporting the trailing portion of the mattress to be wrapped, a front table section pivotally mounted on said frame adjacent its rear end and slidably supporting the leading portion of the mattress, a mandrel rotatably journaled on said frame above said front table section, means for moving the forward end of said front table section upwardly to force the front portion of the mattress toward said mandrel, said front and rear table sections having a gap therebetween through which a web of wrapping paper is adapted to extend, means for guiding the paper from under the rear section through the gap and

11

onto the front table section, said mandrel being expandible and contractible and provided with means for gripping the leading edge of the paper and winding the paper and mattress around said mandrel upon rotation thereof, and means for operating the mandrel to grip and release the paper and to release the rolled and wrapped mattress therefrom.

11. In a mattress wrapping machine, a frame, a stationary rear table section mounted on said frame and slidably supporting the trailing portion of the mattress to be wrapped, a front table section pivotally mounted on said frame at its rear end, beneath said rear table section for supporting the leading portion of the mattress, an expandible mandrel provided with means for gripping the leading edge of the paper, rotatably journaled on said frame above said front table section adjacent the forward end thereof, mechanism for rotatably driving said mandrel by power, means for moving the forward end of said front table section upwardly to force the front portion of the mattress toward said mandrel, said table sections having a gap therebetween extending transversely thereacross, means for guiding a web of paper from under the rear table section through the gap and onto the front table section to said mandrel, means for operating said mandrel to grip and release the paper and to release the rolled mattress, and a cutter mounted to travel transversely of said table sections in the gap therebetween and across the paper, for severing the paper between the front end of the rear table section and the rear end of the front table section.

12. In a mattress winding machine, a frame, a stationary rear table section for slidably supporting the trailing portion of the mattress, a vertically movable front table section pivotally mounted on said frame adjacent its rear end and supporting the leading portion of the mattress, an expandible and contractible mandrel journaled on said frame above said front table section, means for moving the front end of the front table section upwardly to force the front portion of the mattress toward the mandrel, the rear end of the front table section being lower than the front end of the rear table section, said sections having a gap therebetween extending transversely of the mattress, means for guiding a web of paper from under the rear section through said gap and onto the front table section to said mandrel, to be gripped thereby, and means for operating said mandrel to grip and release the paper and to release the rolled mattress for removal from the end thereof.
